UNITED STATES PATENT OFFICE

2,316,537

OVERFALL SAMPLING DEVICE

Bertram H. Hendrickson, Athens, Ga., assignor
to Claude R. Wickard, as Secretary of Agriculture of the United States of America and to his
successors in office

Application October 16, 1941, Serial No. 415,261

5 Claims. (Cl. 73—21)

(Granted under the act of March 3, 1883, as
amended April 30, 1928; 370 O. G. 757)

This application is made under the act of March 3, 1883, as amended by the act of April 30, 1928, and the invention herein described, if patented, may be manufactured and used by or for the Government of the United States of America for governmental purposes without the payment to me of any royalty thereon.

This invention relates to a device which is adapted to be placed in a fluid overfall, the general object of which is to collect a substantially constant fraction of the fluid, which may be water that contains soil, for the purpose of obtaining a sample of the fluid to be submitted to analysis.

A specific object of this invention is the provision of such a device which is automatic in operation and which will collect a substantially constant fraction of the overfall over wide ranges of discharge fluctuations thereof.

In the accompanying drawings, there is illustrated an embodiment of my invention, in which:

Figure 1 is an elevational view of one side of the embodiment;

Figure 2 is an elevational view of the other side of the same embodiment;

Figure 3 is a front elevational view;

Figure 4 is a plan view;

Figure 5 is a vertical longitudinal section of the assembly hereinafter designated as housing 21; and

Figure 6 is a section along the line 6—6 of Figure 1.

Referring with more particularity to the drawings in which like numerals designate like parts, the embodiment illustrated comprises a suitable frame structure 11 in which there is mounted a waterwheel or turbine 12 fixed to an axle 13, said axle being rotatable in bearings 14 and 15 on frame members 16 and 17. Above the waterwheel 12 is mounted a trough 18 which guides the overfall to a point over the waterwheel so as to impinge upon its blades and rotate it, thereby rotating the axle 13. Splash walls 19 and 20 are mounted between the sides of the frame structure and the waterwheel 12.

Between the waterwheel 12 and the trough 18, there is disposed a housing 21 relatively narrow and long which is adapted to scan continuously the width of the overfall as it falls from the trough 18 to the waterwheel 12. The housing 21 slopes downwardly toward the front, substantially as illustrated, and the top is provided with a longitudinal slot 22. Within the housing 21, there is mounted for rotation a pulley 23 at the rear and a pulley 24 at the forward end about

which a belt 25, preferably of the V type, travels. Around the belt 25 there are spaced a number of projections 26, such as pieces of wire, which travel through the slot 22 and scavenge it of any deposits which might prevent the passage of fluid through the slot into the housing 21.

Through the bottom of the housing 21, near the forward end, an outlet 27 is provided, which outlet is connected to a tube 28, such as a common rubber hose, to carry off fluids which collect in the housing 21.

The pulley 24 is fixed to a horizontal shaft 29 which projects through bearings 30 and 31 in the side walls of the housing 21, in which bearings said shaft is rotatably mounted and extends on both sides therefrom where the ends of said shaft are rotatably mounted in bearings 32 and 33 attached to the lower end of vertical supporting members 34 and 35. The upper ends of the supporting members 34 and 35 are connected to a horizontal bar 36, to which there is attached grooved rollers 37 and 38 which ride on a horizontal track or runner 39 secured to brackets 40 and 41 depending from the frame of the device. The rollers 37 and 38 are held on the track 39 by means of a trunnion roller 42 which abuts the underside of a horizontal runway 43 secured to the track 39. This roller 42 is mounted on a bracket 44 which is attached to the horizontal bar 36.

The belt 25 is driven by power applied to the pulley 23 from a horizontal shaft 45. The shaft 45 is of a square cross-section or of some other suitable non-circular shape, and engages a complementary aperture 46 through the pulley 23. The pulley 23, however, is not fixed to the shaft 45, but is axially slidable thereon. The shaft 45 is rotatably mounted in bearings 47 and 48, at which points it may be of a circular cross-section, on frame members 49 and 50, which are disposed in a direction parallel to the slope of the housing 21. Across the frame members 49 and 50 there is disposed a flat bearing surface, such as a plate 51, upon which a roller 52 travels laterally, which roller supports the rearward end of an extension 53 of the housing 21. The rearward end of the extension 53 is also swiveled to the mounting 54 of a pulley 55 by means of a bolt 56, which pulley engages a horizontal track 57 secured across back frame members 58 and 59. The pulley 55 is maintained in contact with the track 57 by means of a spring 60, one end of which abuts the end of the extension 53 and the other end of which abuts the mounting 54.

The shaft 45 extends through the bearing 47

to receive a pulley 61, which is belt-connected to another pulley 62 fixed to the axle 13, substantially as shown. In this manner rotation of the waterwheel 12 causes the shaft 45 to rotate.

The housing 21 is urged to one side of the waterwheel 12 by means of weights 63 and 64 attached to one end of cables 65 and 66 the other end being attached to the extension member 53 and the bar 36, respectively, said cables operating over pulleys or sheaves 67 and 68 on the frame of the device.

On the side of the device opposite the weights 63 and 64, means are provided for moving the housing 21 across the width of the overfall against the action of said weights. These means comprises a pulley 69 fixed to the shaft 45 which is belt-connected to a pulley 70 of the axle 13. There is also mounted on the shaft 45 a cam 71, preferably of a hyperbolic curvature, which is fixed to the pulley 69, by means of bolts 72 so as to rotate therewith. The cam 71 operates against a roller 73 fixed to the end of a lever 74, the other end being pivoted at 75 to the frame of the device. Below the lever 74 another lever 76 is pivoted at one end to the frame beneath the pivot 75 and is connected to the lever 74 by an arm 77, which is pin-connected at 78 to the lever 74 and at 79 to the lever 76. The other end of the lever 76 extends forwardly, to which there is attached the ends of cables 80 and 81. Said cables pass over pulleys 82 and 83 and are attached to the bar 36 and extension 54, respectively.

In operation the overfall is directed through the trough 18 from whence it impinges upon the blades of the waterwheel 12 causing it to rotate. This also causes the shaft 45 to rotate, which is belt geared to the axle 13. Rotation of the shaft 45 causes the pulley 23 to rotate which drives the belt 25 to which the projections 26 are attached. Rotation of the shaft 45 also causes the cam 71 to rotate, which oscillates the roller 73. This oscillation is transmitted to the lever 76. The weights 63 and 64 urge the housing 21 to the left, as viewed in Figure 3. When the cam 71 operates to force the roller 73 downward, the cables 80 and 81 pull the housing 21 in the opposite direction against the action of the weights 63 and 64 until the roller 73 is in its extreme downward position. As the cam 71 continues to revolve the roller 73 moves upward, permitting the weights 63 and 64 to bring the housing 21 back to the left where the cycle is repeated.

As the housing 21 moves first to the right and then to the left across the width of the overfall, it receives a small fraction of fluid from the overflow through the slot 22 which is constantly being scavenged or cleaned by the projections 26 so that a true sample of the overfall is obtained at all times. In moving from one side to the other the pulley 23 slides axially over the shaft 45 while the rollers 37 and 38 travel over the track 39. At the same time the trunnion roller 52 rides on the plate 51 and the pulley 55 rides against the track 57.

Variations in the discharge of the overfall varies the speed of the waterwheel 12 which in turn varies the scanning speed of the housing 21. In this manner the device collects substantially the same percentage or fraction of the overfall at different discharges, assuming that the head of the overfall remains constant.

Having thus described my invention, I claim:

1. A device for obtaining a sample of a fluid overfall comprising a waterwheel actuatable by the overfall, a housing having a slot opening therethrough narrower than the width of the overfall intersecting the trajectory of the overfall, said housing being movable from one side of the overfall to the other, means urging said housing to one side of said overfall, and means actuated by said waterwheel for intermittently moving said housing to the other side of the overfall against the action of said first-mentioned means.

2. A device for obtaining a sample of a fluid overfall comprising a waterwheel actuatable by the overfall, a housing having a slot opening therethrough narrower than the width of the overfall intersecting the trajectory of the overfall, said housing being movable from one side of the overfall to the other, means urging said housing to one side of said overfall, means actuated by said waterwheel for intermittently moving said housing to the other side of the overfall against the action of said first-mentioned means, and means for continuously recovering the fluids which collect in said housing.

3. A device for obtaining a sample of a fluid overfall comprising a waterwheel actuatable by the overfall, a housing having a slot opening therethrough narrower than the width of the overfall intersecting the trajectory of the overfall, said housing being movable from one side of the overfall to the other, means urging said housing to one side of said overfall, means actuated by said waterwheel for intermittently moving said housing to the other side of the overfall against the action of said first-mentioned means, and means actuated by said waterwheel for continuously scavenging said slot.

4. A device for obtaining a sample of a fluid overfall comprising a waterwheel actuatable by the overfall, a housing having a slot opening therethrough narrower than the width of the overfall intersecting the trajectory of the overfall, said housing being movable from one side of the overfall to the other, means urging said housing to one side of said overfall, means actuated by said waterwheel for intermittently moving said housing to the other side of the overfall against the action of said first-mentioned means, means for continuously recovering the fluids which collect in said housing, and means actuated by said waterwheel for continuously scavenging said slot.

5. A device for obtaining a sample of a fluid overfall comprising a waterwheel actuatable by the overfall, a housing having a slot opening therethrough narrower than the width of the overfall intersecting the trajectory of the overfall, said housing being movable from one side of the overfall to the other, means urging said housing to one side of said overfall, means actuated by said waterwheel for intermittently moving said housing to the other side of the overfall against the action of said first-mentioned means, pulleys rotatably mounted within said housing near the ends of the slot, a belt frictionally engaging said pulleys, pins secured to said belt in spaced relation thereabout, said pins extending outwardly from said belt to project through said slot and scavenge it, and means for applying power from said waterwheel to rotate one of said pulleys.

BERTRAM H. HENDRICKSON.
